UNITED STATES PATENT OFFICE.

GEORGE ZINT, OF WAPAKONETA, OHIO.

LAWN-SPRINKLER BEARING ASSEMBLY.

Original application filed March 8, 1926, Serial No. 93,238. Divided and this application filed December 13, 1926. Serial No. 154,537.

This application is a division of my parent U. S. application, Serial No. 93,238, filed March 8th, 1926.

The invention relates to improvements in lawn sprinklers of the type having a sprinkling head which is movable about a vertical axis, under the influence of operating means driven by the spray discharged from a nozzle of the head. The invention has more particular reference to a new and improved bearing construction for holding the sprinkler head anti-frictionally against upward movement under the force of the water passing through the water conducting portions of the sprinkler.

It is the object of the invention to provide a simple and compact, self-lubricating, bearing construction provided with novel means whereby it is protected against water which might otherwise find its way thereto.

With the foregoing in view, the invention resides in the novel subject matter herein-after described and claimed, the description being supplemented by the accompanying drawing, in which a vertical sectional view partly in elevation is shown, of a sprinkler embodying my invention.

In the drawing above briefly described, the numeral 9 designates a stationary body of hollow form to receive and conduct water from a hose or the like, the hose connection or inlet of this body being omitted from the present disclosure as it forms no part of the claimed invention. Threaded into and rising from the body 9, is a tubular connection 10 which rotatably receives a tubular neck 11 on a sprinkler head 12, this head being provided with a nozzle 13. 14 designates a water wheel in the path of the spray from the nozzle 13, for driving suitable operating mechanism 15 for a worm 16, said worm being in mesh with a stationary worm gear 17 fixedly secured between the fitting 10 and the body 9. The wheel 14, the mechanism 15 and the worm 16 are all suitably mounted on a carrier 18 which may rotate about the fitting 10, and the sprinkler head 12 has an appropriate connection with said carrier so that the two must rotate in unison.

Rotation of the wheel 14 causes operation of the mechanism 15 to rotate the worm 16, causing the latter to travel around the worm gear 17, thus rotating the carrier 18 and all parts connected therewith. The parts 19 and 20 merely denote portions of reversing

mechanism for the driving means 15. These parts and in fact all of those so far briefly mentioned, do not include details of the present invention and are merely shown and described in a general way to show one application of such invention.

A vertical rod 34, passes vertically through the body 9 and the neck 11 and has its upper end 35 suitably secured to the sprinkler head 12, while the lower end of this rod passes rotatably through a stuffing box 36 at the lower end of the body 9, said rod projecting downwardly beyond said body. Around the projecting lower end of this rod, is a housing 37 which is preferably of cylindrical form, said housing comprising a lower, lubricant-containing section 38 of cup-like form, and an upper section 39 of similar form, the lower end of this upper section being provided with an extension 40 which is threaded into the upper end of the section 38, a gasket 40' being interposed between the two sections if desired.

The bottom of the upper section 39 and its extension 40 are provided with a stuffing box 41 through which the rod 34 passes, and under this stuffing box, a thrust bearing 42 surrounds the rod and is engaged by a collar 43 thereon, said thrust bearing being preferably of ball bearing form. Thus, all upward thrust upon the sprinkler head 12, being directly imparted to the rod 34, is resisted by the thrust bearing 42, yet this bearing will not interfere with proper rotation of the sprinkler head and associated parts, attention being here invited to the fact that the section 38 of the housing 37, contains a lubricant in which the bearing 42 operates.

Provision is made to prevent any water which may possibly leak through the stuffing box 36, from entering the lower housing section 38 through the stuffing box 41. This provision is within the upper housing section 39 and the latter is provided with discharge openings 39' through which any water that would otherwise collect therein, may discharge. In the present showing, I provide a domelike guard 44 which is secured at the center of its top to the rod 34, the lower end of this guard surrounding an upstanding boss 45 on the bottom of the housing section 39. Thus, any water running down the rod 34 as far as the guard 44, will be shed by the latter onto the bottom of the housing section 39, which section is

provided with the openings 39' permitting the escape of such water.

- The housing 37 may be connected in any desired manner with the body 9. In the present showing, the upper end of this housing is received in a socket 46 in the lower end of the body and may be held against rotation in any desired manner. Descent of the entire housing 37, it will be observed, is prevented by the rod 34, the bearing 42 and the collar 43, and it will be observed that whenever desired, the housing section 38 may be removed for the purpose of replenishing its supply of lubricant.
- 15 The novel construction shown and described has proven very efficient and advantageous and is therefore preferably followed. However, within the scope of the invention as claimed, variations may be made.

I claim:—

1. An assembly of the class set forth comprising a hollow liquid-conducting body having a stuffing box at its lower end, a rod 25 passing downwardly through said stuffing box, a housing abutting the lower end of said body and formed of upper and lower cup-like sections detachably connected with each other, the upper section having an opening 30 in its bottom through which said rod passes into the lower section, a thrust bearing within said lower section having operative connection with said rod to hold the latter against upward movement, and means 35 within said upper cup-like housing section to prevent liquid from running down the rod into the lower housing section, said upper section having an outlet for the arrested liquid.
- 40 2. An assembly of the class set forth comprising a hollow liquid-conducting body having a stuffing box at its lower end, a rod passing downwardly through said stuffing box, a housing abutting the lower end of said

body and formed of upper and lower cup-like sections detachably connected with each other, the upper section having an opening in its bottom through which said rod passes into the lower section, a thrust bearing within said lower section having operative connection with said rod to hold the latter against upward movement, an upstanding boss on the bottom of said upper housing section around its opening, and a continuous guard secured to the rod within said upper section and having a portion surrounding said boss to shed any water running down the rod into said upper section, the latter having an opening through which the arrested water may drain.

3. An assembly of the class described comprising a liquid-conducting body having a stuffing box at its lower end, a rod passing downwardly through said stuffing box, an upper cup-like housing section abutting the lower end of said body, the bottom of said upper section having a stuffing box through which said rod passes downwardly, said bottom being provided also with a downward externally threaded projection, a lower cup-like housing section threaded upon said projection and receiving the lower end of said rod, a thrust bearing connected with the rod and disposed in said lower housing section to hold said rod against upward movement, 70 a boss rising from the bottom of said upper section and surrounding the rod, and a dome-like guard having the center of its top secured to said rod above said boss, said guard being disposed within said upper housing section and having its lower edge disposed around the aforesaid boss, said guard serving to shed any liquid running down the rod, 75 said upper section having an opening through which such liquid may drain.

In testimony whereof I have hereunto affixed my signature.

GEORGE ZINT.
